DESIGN.

No. 32,822.

Patented June 12, 1900.

W. MORGAN & J. G. HEASLET.
STEERING AXLE FOR MOTOR VEHICLES.

(Application filed Dec. 19, 1899.)

UNITED STATES PATENT OFFICE.

WILLIAM MORGAN, OF PITTSBURG, AND JAMES G. HEASLET, OF ALLEGHENY,
PENNSYLVANIA, ASSIGNORS TO THE AUTOCAR COMPANY, OF PITTS-
BURG, PENNSYLVANIA.

DESIGN FOR A STEERING-AXLE FOR MOTOR-VEHICLES.

SPECIFICATION forming part of Design No. 32,822, dated June 12, 1900.

Application filed December 19, 1899. Serial No. 740,932. Term of patent 14 years.

To all whom it may concern:

Be it known that we, WILLIAM MORGAN, a resident of Pittsburg, and JAMES G. HEASLET, a resident of Allegheny, in the county of Allegheny and State of Pennsylvania, have invented a new and original Design for a Steering-Axle for Motor-Vehicles; and we do hereby declare the following to be a full, clear, and exact description thereof.

10 The figure illustrates a perspective view of our new steering-axle for motor-vehicles.

The essential feature of our new design for a steering-axle for motor-vehicles consists in the construction herein described and shown.

15 1 represents one arched member, and 2 the other arched member, which is provided with the curved portion 3 and straight portions 3' thereon. The outer ends of the arched member 1 and the outer ends of the straight portions 3' of the arched member 2 are joined in

union socket-pieces 4, having forked extensions 5 thereon. Upon the curved portion 3 of the arched member 2 is the collar 6, which is provided with the flanges 7 thereon, and upon the arched member 1 is the collar 8, 25 which is provided with the flange 9 thereon. Braces 10 are secured between the two arched members 1 2.

We claim—

The design for a steering-axle for motor- 30 vehicles, substantially as herein shown and described.

In testimony whereof we, the said WILLIAM MORGAN and JAMES G. HEASLET, have hereunto set our hands.

WILLIAM MORGAN.
JAMES G. HEASLET.
